Fig. 1

Fig. 2

Fig. 3

Fig. 4

Fig. 6.

Fig. 5.

FIG. 1 is a perspective view of a raft incorporating the design;

FIG. 2 is a top plan view thereof, it being understood that, in FIG. 1 as well, the tread shown as covering one of the pie-shaped segments also covers the other pie-shaped segments.

FIG. 3 is a side elevational view thereof with a portion partly broken away on the line 3-3 of FIG. 4.

FIG. 4 is an under plan view thereof; and

FIG. 5 is an under plan view of a modified form thereof, the other views of the modified form thereof being identical with FIGS. 1-3.

FIG. 6 is a side elevational view, similar to FIG. 3, of the modified form of the invention shown in FIG. 5, with a portion being broken away in like manner.

The view from any side in both embodiments is identical to the illustrated side.

This application is a continuation-in-part of my application, Ser. No. 17,125, filed May 12, 1969 for a Raft, now abandoned.

I claim:

The ornamental design for a raft, as shown and described.
